(57) **CLAIM**

The ornamental design for a ride-on vehicle, as shown.

DESCRIPTION

FIG. 1 is a front perspective view of the ride-on vehicle.

FIG. 2 is a left side elevation view of the ride-on vehicle
depicted in FIG. 1.

FIG. 3 is right side elevation view of the ride-on vehicle
depicted in FIG. 1.

FIG. 4 is a rear elevation view of the ride-on vehicle
depicted in FIG. 1.

FIG. 5 is a front elevation view of the ride-on vehicle
depicted in FIG. 1.

FIG. 6 is a top plan view of the ride-on vehicle depicted in
FIG. 1.

FIG. 7 is a bottom plan view of the ride-on vehicle depicted in
FIG. 1.

The broken lines shown in FIGS. 1, 2, 3, 5 and 6 are for
illustrative purposes only and form no part of the claimed
design.
